Primary Examiner — Barbara Fox*Assistant Examiner* — Jamaal Rasheed(74) *Attorney, Agent, or Firm* — Schultz & Associates, P.C.(57) **CLAIM**

The ornamental design for a faucet, as shown and described.

DESCRIPTION

FIG. 1 is a front perspective view of a faucet, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

FIG. 8 is a detail view of a faucet section of FIG. 1; and, FIG. 9 is a detail view of a faucet section of FIG. 2.

The broken lines shown in the figures depict portions of the faucet that form no part of the claimed design.

1 Claim, 7 Drawing Sheets(56)
